UNITED STATES PATENT OFFICE.

CHARLES PAULY, OF PORT WASHINGTON, WISCONSIN.

VAT.

Application filed May 14, 1925. Serial No. 30,388.

This invention relates to vats and is particularly directed to a vat for use in cheese making.

Objects of this invention are to provide a vat which is of very simple construction, which may be kept in a sanitary condition in an easy manner, which is not cluttered up with pipes and coils, but which provides a substantially flat unbroken surface to facilitate ready cleaning and scouring.

Further objects are to provide a vat in which water is circulated and heated by means of steam so that the steam furnishes both the heat and the power for circulating the water, in which pumps are not required, and in which the extensive area presented by the vat has substantially all of its portion contacting with a flowing stream of heated water.

An embodiment of the invention is shown in the accompanying drawings, in which:—

Figure 1 is a plan view of the vat with parts broken away.

Figure 2 is a side elevation thereof such view being partly in section.

Figure 3 is a sectional view on the line 3—3 of Figure 1.

Figure 4 is an end view of the vat with a part broken away.

Figure 5 is an enlarged fragmentary sectional view illustrating details of construction.

Referring to the drawings, it will be seen that the vat comprises an outer compartment 1 which may be of wood or sheet metal or any suitable material. Within this compartment a relatively long and shallow vat 2 is positioned. This vat is in reality a metal pan and is spaced from the main compartment 1 by means of a plurality of relatively small angle irons 3 along its bottom and also by means of angle irons 4 along its sides. It is to be noted that the pan 2 may be readily lifted from the compartment 1 and for this purpose it is preferably reenforced around its top edges by means of the members 5.

It is to be particularly noted from reference to Figures 1 and 2 that the angle irons 3 and 4 alternately extend from opposite ends of the vat. These angle irons at their other end are spaced from the ends of the vat so as to provide circulating channels continuously from the center of the vat back and forth across its bottom, and back and forth across its sides.

It is to be noted that the outermost angle irons provide a space for the liquid to pass into the side portions between the sides of the pan 2 and the outer shell 1. This is most clearly brought out in Figures 1 and 3, Figure 3 showing the outermost angle irons unsectioned and illustrating this free passageway.

The upper rear ends of the outer container or shell 1 are connected by means of pipes 6 with a small reservoir 7, such reservoir being provided with an overflow 8 adjacent its upper portion. A pipe 9 extends downwardly from the reservoir 7, as shown in Figures 2, 3 and 4, and passes to an injector 10. This injector is provided with an outlet or delivery pipe 11 which extends along the bottom of the vat. The injector is supplied by means of a steam pipe 12 and a cut-off valve 13 is employed for controlling the steam. The forward end of the pipe 11 connects to one end of a three-way valve 14. This three-way valve normally connects the pipe 11 with the pipe 15. The pipe 15 opens between the center channel irons 3, as shown in Figure 1, such opening being indicated by the reference character 16. A cold water supply pipe 17 connects to the outer end to the three-way valve 14 and is normally closed by such valve.

The operation of the apparatus is as follows:—The pan 2 is filled with milk or with material to be treated and the space between the container or shell 1 and the pan 2 is filled with water by manipulating the three-way valve 14 to connect the pipe 17 with the pipe 15. Thereafter, the three-way valve connects the pipe 15 with the pipe 11 and the valve 13 for the steam is opened. The steam operates the injector 10 and draws water from the reservoir 7 heating the water and propelling it through the pipe 11. The water passes through such pipe, through the valve 14, through the pipe 15 and is discharged at 16 between the central irons 3. This heated water flows, as indicated by the arrows in Figures 1 and 2, back and forth across the bottom of the pan and across the sides thereof, thus heating substantially the entire area or surface of the pan and quickly bringing the contents of this shallow pan to pasteurizing temperature. Any excess water due to the condensation of the steam overflows through the pipe 8.

When the milk or cheese has been main-

tained at the proper temperature for a sufficient length of time, the steam valve 13 is closed and the three-way valve 14 may then be opened if it is desired to chill the contents of the pan. This three-way valve is turned to cut off the pipe 11 and to connect the pipes 17 and 15. Cold water now displaces the heated water and circulates back and forth across the outer surface of the pan, thus 10 quickly chilling the contents thereof.

When it is considered that cheese makers are required to pasteurize the milk prior to the cheese making operation, it will be appreciated that considerable difficulty is experienced in the usual equipments found in cheese factories due to this requirement. However, in practicing this invention, the difficulty of adapting the apparatus now found in cheese factories to this new condition may be readily effected with a minimum 20 of expense and without unnecessary complication of the apparatus.

It is to be noted further that the angle irons 3 and 4 serve a double purpose of both reenforcing the pan and also of providing the channels for the circulating liquid.

It is to be noted further that the apparatus is extremely simple and may be produced at a minimum of machine work.

30 Although the invention has been described in considerable detail, it is to be understood that the invention may be variously em-

bodied and is, therefore, to be limited only as claimed.

I claim:

A vat comprising an outer shell having inlet and outlet apertures at opposite ends, and an inner pan removably positioned within and spaced from said outer shell, said removable pan having a plurality of longitudinally extending angle irons having vertical flanges resting upon the bottom of the outer shell and having horizontal flanges secured to the under side of the removable pan and having a plurality of longitudinally extending angle irons secured by means of their flanges to the sides of said pan and having the other flanges of such last mentioned angle irons contacting with the sides of the shell, said angle irons being alternately spaced from the ends of the outer shell, whereby a tortuous channel is provided from the inlet opening in the vat to the outlet opening, said pan having a reenforcing outwardly projecting marginal portion extending completely around its upper edge, whereby said pan may be freely grasped and manipulated by means of the reenforced marginal portion.

In testimony that I claim the foregoing 60 I have hereunto set my hand at Milwaukee, in the county of Milwaukee and State of Wisconsin.

CHARLES PAULY.
